UNITED STATES PATENT OFFICE.

MATHEW SPINELLO, OF KANSAS CITY, MISSOURI.

DISPLAY DEVICE.

1,389,078.

Specification of Letters Patent. Patented Aug. 30, 1921.

Application filed December 8, 1920. Serial No. 429,270.

To all whom it may concern:

Be it known that I, MATHEW SPINELLO, a citizen of the United States, residing at Kansas City, in the county of Jackson and State 5 of Missouri, have invented certain new and useful Improvements in Display Devices; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 This invention relates to a mechanically operated display device whereby a constantly changing sign or display may be presented to view in an attractive manner, advantage being taken of the well known 20 curiosity of the human race in order to attract persons to the sign.

The invention contemplates the provision of means whereby the display will be periodically and intermittently obscured from 25 view by a curtain, which may be raised and lowered automatically between the rotative movements of the display device.

The front of the advertising or display device will preferably simulate a stage or 30 forum so that passersby will be attracted to it but the particular form of the device is not so important, the invention residing in the peculiar combinations of parts and, in some respects, their details, as will be apparent by reference to the drawings, in 35 which—

Figure 1 is a front view of a display device constructed in accordance with my invention, the curtain being in raised position.

40 Fig. 2 is a perspective view of the organized mechanism, the front of the device being removed.

Fig. 3 is a vertical, longitudinal, sectional view through the operating mechanism, the display elements being shown in elevation.

Fig. 4 is a perspective view of the curtain actuator operating cam.

Fig. 5 is a plan view of the display element carrier and the display element shifter, and

Fig. 6 is a detail perspective view of one of the display elements and a spring stop therefor.

55 In carrying out my invention I prefer to provide a casing of suitable construction in

which the mechanism is contained. The front of the casing, designated 1, may be open, as indicated at 2, Fig. 1, the opening being intermittently closed during the operation of the mechanism by a drop curtain 3 on a roller 4, carried by a shaft 5, journaled in the frame or casing 1. At one end of the shaft 5 is a pinion 6, the teeth of which are adapted to mesh with the teeth of a rack bar 7, vertically mounted in guides 8 and 9 on the casing 1 and adapted to slide therein. The lower end of the bar 7 is provided with a right angular extension 10, on which is a roller 11 to ride on the oppositely 60 located cam tracks 12 and 13, carried by the rotatable disk 14 so that the bar 7 will be raised when the roller rides upon the upper edge of either track and will be allowed to gravitate when the roller moves 65 off the track, the reciprocal movement of the bar 7 being effective in imparting a rotative movement to the shaft 5 whereby 70 the roller may wind and unwind the curtain.

The disk or table 14 is supported upon a vertical, axially disposed shaft 15, which is mounted in a step bearing 16 on the bottom 17 of the casing 1, the shaft being rotated by a motor 18, preferably an electric motor, 75 from the drive shaft of which a pulley 19 may be driven through the medium of the belt 20. The pulley 19 is on a horizontal shaft 21, which carries a worm 22, meshing with a worm gear 23 on the shaft 15. 80

The shaft 21 is journaled in suitable bearings to maintain it in proper relative position, the particular mounting shown in Fig. 2 consisting of an inverted, U-shaped bracket 24, mounted upon the base 17. Therefore, 85 when the motor is operated, motion will be communicated to the shaft 15 in an obvious manner to rotate the disk or table 14 rigid thereon.

Beneath the table or disk 14 is a disk or 90 plate 25 having a central opening 26, through which the shaft 15 projects. The plate is supported upon a bracket 27 having a chute 28 secured to the floor 17 and the bracket 27 is preferably fastened to the 95 bracket 24 by an angle 29 to afford rigidity thereto. The disk or plate 25 carries two spring cams 30 and 31, each of which is fastened at one end to the disk or plate and each of which has a yielding free end, the free ends 100 of the cams extending in opposite directions. Said cams are provided with inclined por-

tions 32 and 33, up which may ride the end 34 of a downwardly, spring-pressed rod 35, carrying a collar 36 against which one end of a coil spring 37 on rod 35 bears, the opposite end of the spring bearing against a web or partition 38 carried by the cylindrical member 39 supported upon the disk or table 14 and rotative therewith.

The rod 35 is adapted to be raised by the cams 30 and 31 into engaging position with certain display element actuators so as to rotate them about a common axis and bring them successively into view through the opening 2.

15 The display or indicia-carrying elements are upon a disk or table 40 within the recess 41 of the cylindrical member 39, the table being supported upon a vertical, axially positioned shaft 42, one end of which is mounted in a friction bearing 44, the other end having a point bearing 45 received within the bearing recess 46. Beneath the table 40 are studs or fastening devices 47 carrying bifurcated spring arms consisting of the 25 spring leaves 48 and 49, Fig. 6, connected by a cylindrical connection 50, engaged by the studs 47. The arms 48 and 49 are adapted to yieldingly engage the flat ends 51 of the the rotatable shafts 52, carried by the 30 table and which support the substantially rectangular frame 53, there being four frames 53 shown, each of which is provided with a shaft 52 and a flat end 51, and each of which co-operates with a set of bifurcated 35 spring arms 48 and 49.

Each frame is provided with grooved rails 54, 55, 56 and 57 so that cards or panels 58 may be removably received by the frame, there being two cards carried by each frame, 40 it being understood that each frame is reversible so that the four frames are capable of progressively displaying eight different advertisements or eight different displays, there being a reversing member shown as 45 an idler 59 carried by a bracket 60 on the cross bar 61, the idler being adapted to engage the inner face of each successive frame 58 as it is presented to it.

Assuming the parts to be assembled with 50 each frame carrying two displays or cards, if the motor is operating, motion will be communicated to the pulley 19 to drive the shaft 21 which, in turn, will communicate motion to the gear 23 so as to drive the vertical shaft 15. As the vertical shaft 15 rotates, it will carry with it the disk or table 14, in which the spring-pressed bar 35 is mounted. As the bar rides over one of the cams 30 or 31, it will be raised to bring the 55 upper end in contact with one set of spring arms 48 and 49, thereby rotating the disk or table 40 ninety degrees. By the time that the bar 35 has moved the table 40 ninety degrees to bring a card opposite the 60 opening 2, the end 34 of the rod 35 will

have moved off the cam on plate 25 so that the spring 37 will be effective in moving the rod 35 out of contact with the spring arm or engaging element 48 or 49. The table 14, however, will continue to rotate, 70 the cams 12 and 13 and 30 and 31 being so timed that when the bar 35 moves out of actuating contact with the abutting arm 48 or 49, the roller 11 will begin to move up the inclined end of one of the cams 12 or 75 13, imparting an upward longitudinal movement to the bar 7. This will be effective in rotating the shaft 5 through the rack portion of the bar 7 and the pinion 6 so that the curtain will be raised.

The curtain will remain raised as long as the roller 11 rides over the upper edge of one of the cams 12 or 13. At the end of the cam 12 or 13, as the case may be, the roller will drop off, the weight of the bar 7 being 85 sufficient to allow it to gravitate and thereby reverse the rotative movement of the roller 4 to unwind the curtain or cause it to drop. Then the rod 35 again moves over a cam 30 or 31 to turn the table 40 ninety degrees, 90 during the interval that the curtain closes the opening.

Each time that the table 40 moves ninety degrees, one of the frames is reversed because as the table 40 starts to turn, a frame is engaged by the reversing roller 59, engaging the inner face thereof, as shown in Fig. 5, so that the roller will rotate on its pivot or shaft 52 and when it has made its rotative movement of about one hundred eighty degrees, the frame will be held between the spring arms 48 and 49, which will bear against the flat portion 51.

It will be apparent, therefore, that the shifting of the display frame table 40 takes 105 place intermittently to the shifting of the curtain; that is, when the curtain is raised, the table 40, presenting a display card, is stationary, the curtain then descends while the card is still stationary; then the table 40 110 shifts to present a new card, at the same time reversing one of the cards through the medium of the pulley 59, then stands stationary while the curtain is raised. This arrangement presents an attractive display device which is well adapted to serve the purpose for which it is intended, it being understood that the mechanism for driving the parts will be obscured and that the cylindrical member 34 and table 40 may be 120 covered with suitable indicia if desired.

What I claim and desire to secure by Letters-Patent is:

1. A display device comprising a casing, a rotatable table within the casing, a rotatable disk above the rotatable table having movement independent thereof, and means on the rotatable table for intermittently rotating the rotatable disk.

2. A display device comprising a casing, a

rotatable table within the casing, a rotatable disk above the rotatable table having movement independent thereof, means on the rotatable table for intermittently rotating the 5 rotatable disk and display frames carried by the disk.

3. A display device comprising a casing, a rotatable table within the casing, a rotatable disk above the rotatable table having movement independent thereof, means on the 10 rotatable table for intermittently rotating the rotatable disk, and reversible display frames carried by the rotatable disk.

4. A display device comprising a casing, a 15 rotatable table within the casing, a rotatable disk above the rotatable table having movement independent thereof, means on the rotatable table for intermittently rotating the rotatable disk, reversible display frames 20 carried by the rotatable disk, and means independent of the frames for progressively engaging the frames as they pass a given point to reverse them.

5. A display device comprising a casing 25 having an opening, a constantly rotating table within the casing, an intermittently rotating, display-carrying means above the table, means controlled by the table for intermittently effecting movement of the disk, 30 and an intermittently operating curtain controlled from the table for opening and closing the opening in the casing.

6. A display device comprising a casing

having an opening, a constantly rotating table within the casing, an intermittently 35 movable display means above the table, means coöperating with the table for intermittently imparting movement to the display means, an intermittently movable curtain to cover and uncover the opening, and 40 means controlled by the table for actuating the curtain.

7. In a display device, a constantly rotating member, an intermittently rotating member, means controlled by the constantly rotating member to intermittently actuate the intermittently movable member, an intermittently movable curtain for intermittently obscuring the intermittently movable member, and means controlled by the constantly 45 movable member for actuating the curtain.

8. A display device comprising a constantly rotating table, a display device separate from but intermittently controlled by the movement of the table, said display device comprising a support, a plurality of rotatable frame-carrying shafts on said support, means for imparting a rotative movement to the frames about their shafts, and means for opposing rotative movement of 50 the shafts, said last named means comprising bifurcated stop members having spring arms for engagement with the flat faces on the shafts.

In testimony whereof I affix my signature. 65
MATHEW SPINELLO.
